UNITED STATES PATENT OFFICE.

GEORGE E. JOHNSON, OF NEW YORK, N. Y.

DESIGN FOR A DOOR OR WINDOW SECURER.

SPECIFICATION forming part of Design No. 31,529, dated September 19, 1899.

Application filed August 22, 1899. Serial No. 728,131. Term of patent 7 years.

To all whom it may concern:

Be it known that I, GEORGE E. JOHNSON, a citizen of the United States, residing at the city of New York, borough of Brooklyn, in the county of Kings and State of New York, have invented and produced a new and original Design for a Door or Window Securer, of which the following is a specification, reference being had to the accompanying drawings, forming a part thereof, in which—

Figure 1 is a perspective view of a door and window securer embodying the features of my design, and Fig. 2 is an edge view of the same.

The leading features of the design consist in the rectangular body A, the handle B, having flat sides lying in planes at right angles to the edges of the body, the transverse rib C, appearing upon a side surface of the body

near the handle, and the wedge-shaped tongue D at the outer end of the body and upon the same surface as the rib C.

The minor features of the design consist in the shape of the handle, the curved line a of the plain side surface of the body, and the inclined apertured surface b between the rib C and the handle.

I claim—

The design for a door and window securer, substantially as herein shown and described. 30

In testimony whereof I have signed my name to this specification in the presence of two subscribing witnesses.

GEORGE E. JOHNSON.
